UNITED STATES PATENT OFFICE.

PHILIZA H. FONTAINE, OF PETERSBURG, NORTH DAKOTA.

SHAFT-CENTER-FINDING DEVICE.

Application filed May 24, 1923, Serial No. 641,158. Renewed July 9, 1924.

To all whom it may concern:

Be it known that I, PHILIZA H. FONTAINE, a citizen of the United States, residing at Petersburg, in the county of Nelson, 5 State of North Dakota, have invented a new and useful Shaft-Center-Finding Device; and I do hereby declare the following to be a full, clear, and exact description of the invention, such as will enable 10 others skilled in the art to which it appertains to make and use the same.

The invention relates to shaft center finding devices, and has for its object to provide a device of this character, by means of 15 which the exact center of a shaft may be easily and quickly ascertained and marked.

A further object is to provide a shaft center locating device comprising a scaled bar, on which bar sleeves are slidably 20 mounted and provided with arms for engaging the opposite sides of a shaft. The sleeves have link connections with a vertically slidable member mounted on a sleeve at right angles to the bar, and consequently 25 upon an upward or downward movement of the slideable member the sleeves will be moved inwardly or outwardly. Also to provide a center punch in the bar carried sleeve, by means of which center punch the center 30 of the shaft held between the shaft engaging arms may be accurately marked.

A further object is to form the shaft engaging arms semicircular shaped in transverse cross section, thereby forming spaced 35 shaft engaging edges at opposite sides of the shaft for accurately holding the device centered.

With the above and other objects in view the invention resides in the combination 40 and arrangement of parts as hereinafter set forth, shown in the drawings described and claimed, it being understood that changes, in the precise embodiment of the invention, may be made within the scope of what is 45 claimed without departing from the spirit of the invention.

In the drawing:—

Figure 1 is a perspective view of the center finding device.

50 Figure 2 is a vertical longitudinal sectional view through the lower portion of the device, showing the same applied to a shaft.

55 Referring to the drawing, the numeral 1 designates a bar, which bar is provided with a scale 2, whereby the center of the shaft

may be accurately gaged. Extending outwardly from one side of the bar 1 is a sleeve 3, which sleeve is disposed at a right angle to the bar 1, and is adapted to receive and 60 guide a center punch 4, in a manner whereby its point 5 will register with the center of the bar 6, after said bar is centered in the device. Slidably mounted on the bar 1 at opposite ends thereof are rectangular 65 shaped sleeves 7, which sleeves are provided with parallel shaft engaging arms 8, adapted to engage opposite sides of the shaft 6 for centering the shaft in relation to the center punch 4. Sleeves 7 have pivotally connected thereto at 9 links 10, which links are pivotally connected at 11 to a member 12, 70 slidably mounted on the sleeve 3. The links 10 are of equal length and consequently it will be seen that when the arms 8 are moved inwardly into engagement with the shaft disposed therebetween the member 12 will move upwardly thereby allowing the sleeves 7 to move inwardly at equal distances from the center of the center punch 4, consequently 75 the device will automatically center itself on the shaft 6 with the point 5 of the center punch 4 in registration with the center of the shaft, at which time the center of the 80 shaft may be marked if so desired by imparting a percussive blow on the end 13 of the center punch.

The shaft engaging arms 8 are preferably 85 semicircular shaped in cross section as shown, therefore it will be seen that the 90 edges 14 thereof are in parallel relation to each other, and that space engaging edges are provided whereby, when said edges engage opposite sides of the shaft is larger than the radius of the arms 8, the device will be 95 held against tilting and will automatically adjust itself.

From the above it will be seen that a 100 shaft centering and finding device is provided which is simple in construction and one wherein the center of shafts of various diameters may be quickly located and marked.

The invention having been set forth what 105 is claimed as new and useful is:—

A center locating and marking device for 110 shafts comprising a bar, sleeves slidably mounted on the bar at opposite ends thereof, shaft engaging arms carried by said sleeves and disposed at a right angle to the bar and in parallel relation to each other, a right angularly disposed sleeve

carried by the bar at the opposite sides to the shaft engaging arms, a member slidably mounted on said right angularly disposed sleeve, link connections between said member and the sleeves on the bar, and a center marking member extending through the right angularly disposed sleeve in the bar and forming means whereby the center of the shaft may be marked when the shaft

engaging arms are in engagement with opposite sides of the shaft. 10

In testimony whereof I have signed my name to this specification in the presence of two subscribing witnesses.

PHILIZA H. FONTAINE.
